(57) **CLAIM**

The ornamental design for a tread of a tire, as shown and described.

DESCRIPTION

FIG. 1 is a perspective view of a tread of a tire, it being understood that the pattern is repeated uniformly throughout the circumference of the tread, and,

FIG. 2 is an elevational view of the tire tread shown in FIG. 1.

The broken line showing the tire inner bead and sidewall in FIG. 1 is for illustrative purposes only and forms no part of the claimed design.
